Primary Examiner — Wan Laymon(74) *Attorney, Agent, or Firm* — Michael Best & Friedrich LLP(57) **CLAIM**

We claim the ornamental design for a driver bit, as shown and described.

DESCRIPTION

FIG. 1 is a perspective view of a driver bit embodying the invention.

FIG. 2 is a first side view of the driver bit of FIG. 1.

FIG. 3 is a second side view of the driver bit of FIG. 1.

FIG. 4 is a first end view of the driver bit and of FIG. 1.

FIG. 5 is a second end view of the driver bit of FIG. 1.

FIG. 6 is a top view of the driver bit of FIG. 1; and,

FIG. 7 is a bottom view of the driver bit of FIG. 1.

Portions of the driver bit shown in broken lines form no part of the claimed design. The broken away symbols in the drawings indicate that any portion of the article beyond what is shown forms no part of the claimed design.
